GROUND GRIP

Charles Lyman Ellis, Brownsville, Tex.

Application April 4, 1945, Serial No. 586,582

4 Claims. (Cl. 72—105)

This invention relates to an improved means for securing wooden strips, such as sleepers, furring strips, or the like, to concrete walls or floors.

An object of this invention is to provide an improved anchor which is adapted to be partly embedded in concrete and partly projecting therefrom, the projecting portion of the device being formed with tangs for holding wooden strips firmly with respect to the concrete.

Another object of this invention is to provide an attaching means of this kind which is of simple construction, so that it can be cheaply and quickly made and will provide the necessary firm grip or holding means for the wooden strips.

A further object of this invention is to provide a device of this kind embodying a fixed washer or plate, which provides a limiting means for limiting the extension of the anchoring portion thereof in the concrete.

To the foregoing objects and others which may hereinafter more fully appear, the invention consists of the novel construction, combination and arrangement of parts, as will be more specifically referred to and illustrated in the accompanying drawing, but it is to be understood that changes, variations, and modifications may be resorted to which fall within the scope of the invention as claimed.

In the drawing:

Figure 1 is a fragmentary sectional view of a concrete floor, having a strip anchoring means embedded therein, which is constructed according to an embodiment of this invention.

Figure 2 is a plan view of the device shown in Figure 1.

Figure 3 is a detail side elevation of a modified form of this invention.

Referring to the drawing, the numeral 10 designates generally a concrete floor, or other structure such as a wall, or the like, and the numeral 11 designates a wooden strip which is adapted to be secured to the outer surface 13 of the concrete 10.

In order to provide a means whereby the strip 11 will be firmly anchored with respect to the concrete 10, I have provided a strip anchoring means, including an elongated bar 12, which is provided at its inner end with a head or washer 14. The bar 12 also has fixed thereto a circular washer or plate 15, which is disposed between the ends of the bar 12 and provides a stop, which is adapted to limit the extension of the anchoring portion 16 of the bar 12 into the concrete 10.

The bar 12 includes a projecting pointed member 17, which extends outwardly or upwardly from the stop plate 15, and the point 17 is provided with a plurality of outwardly projecting tangs 18. The point 17 is adapted to be driven into the strip 11 from the inner side thereof and

is of such length that the point 17 will be substantially entirely embedded in the strip 11, the latter being substantially thicker than the length of the point 17, so that no portion of the point 17 will project through the strip 11.

Referring now to Figure 3, there is disclosed a modified form of this invention, which includes an anchoring bar 19, which is longitudinally bent of substantially corrugated configuration, and is formed with an inner anchoring member 20.

A plate 21 is fixed to the outer end of the anchoring member 19 and is adapted to engage the outer surface of the concrete, so as to limit the extension of the anchoring member 19 within the concrete. A point 22 is formed integral with the anchoring member 19 and is provided with a plurality of laterally projecting tangs 23, which are struck from the outer surface thereof and are inwardly bent so that when the point 22 is driven into the wooden strip, the tangs 23 will hold the point firmly in the strip.

In the use of this device the anchoring construction has the anchoring member thereof embedded in the concrete 10, and when the concrete has set, the strip 11 may be engaged with the point 17 and the strip 11 struck with a tool, so as to force the strip 11 downwardly and the point 17 into the strip. These strips can be held in alignment in any suitable manner, and after the strip 11 has been forced over the point 17 the inwardly projecting tangs 18 will hold the strip 11 firmly on the point 17.

The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claims.

What I claim is:

1. An anchor for securing a part to a concrete structure, comprising an anchoring member adapted to be embedded in the concrete, a plate carried by the outer end of said member and adapted to engage the outer surface of the concrete to limit the extension of said member into the concrete, a point extending from the outer end of said member, and inwardly directed barbs carried by said point.

2. An anchor as set forth in claim 1 including a plate fixed to the inner end of said member.

3. An anchor as set forth in claim 1 wherein said member is of substantially corrugated shape.

4. An anchor as set forth in claim 1 wherein said member is of substantially serpentine shape and the inner end thereof is extended at substantially right angles to the length thereof.
